UNITED STATES PATENT OFFICE.

JOSEPH STEGER, OF NEW YORK, N. Y.

IMPROVEMENT IN CAR-BRAKES

Specification forming part of Letters Patent No. 104,897, dated June 28, 1870.

To all whom it may concern:

Be it known that I, JOSEPH STEGER, of the city, county, and State of New York, have invented a new and useful Improvement in Car-Brakes; and I do hereby declare the following to be a full, clear, and exact description thereof, which will enable those skilled in the art to make and use the same, reference being had to the accompanying drawings, forming part of this specification, in which drawings—

Figure 1 represents a longitudinal vertical section of this invention. Fig. 2 is an inverted plan of the same. Fig. 3 is a transverse section of the same.

Similar letters indicate corresponding parts.

This invention consists in a pendent lever, which is capable of being operated by a brake rope or chain extending throughout the whole length of a car, or of a train of cars, and which carries a friction-roller and winding-rollers, in such relation to each other and to the fulcrum of the lever that when the brake-rope is pulled, and thereby the friction-roller is caused to bear upon the axle, or any part connected to said axle, the winding-rollers begin to act, and the brakes are applied, and by the very act of applying the brakes the friction-roller is drawn up tighter and tighter against the axle, and thereby the brake-rope is relieved from considerable strain. With the pendent lever is combined another lever, carrying rollers over which the brake-rope passes, so as to increase the strain of the brake-rope by the leverage due to said lever. The friction-roller is mounted upon two conical disks pressed up against corresponding sockets in the sides of the roller by means of a spring or springs, the tension of which is adjustable by a nut in such a manner that the power required to cause the friction-roller to slip on its shaft can be regulated; and, furthermore, said roller, being held uniformly from both sides, is not liable to lose its correct position. The car-wheel is provided with a long hub to form a bearing for the friction-roller, and saving the necessity of securing a separate pulley on the axle.

In the drawings, the letter A designates the frame of a truck, which runs on wheels B, mounted on the axle C in the ordinary manner. From this truck-frame is suspended a pendent lever, D, which has its fulcrum on pivots *a*, and forms the bearings for two shafts,

b c—one at or near its lower end, and the other at a short distance below its fulcrum—as shown in Fig. 1 of the drawings.

On the lower shaft, *b*, is mounted a friction-roller, *d*, and from said shaft *b* extends a rope, *h*, round a roller, *i*, which is mounted on the upper shaft, *c*, and on this shaft is also mounted a roller, *j*, which connects by means of a rope, *k*, with the equalizing-lever of the brakes, or with the brake-lever E, as shown.

The pendent lever D connects by a rod, *l*, with the upper end of a lever, *f*, which has its fulcrum on a pivot, *f'*, on which is mounted a roller, *f''*, while in the lower end of said roller is mounted a roller, *f'''*. The brake-rope *g* extends over the roller *f''*, and under the roller *f'''*, as shown in Fig. 1, so that it passes through under the track-frame to the next car ahead, and out over the truck-frame to the next car behind, the object of this arrangement being to prevent the bumper from interfering with the brake-rope when the position of the locomotive is changed from one end of the train to the other. When the brake-rope is drawn up tight, the lever *f* swings in the direction of the arrow marked on it in Fig. 1, the friction-roller *d* is brought to bear upon the axle C, and the shaft *b* is caused to revolve. The rope *h* is wound upon this shaft, and in being unwound from the roller *i* the shaft *c* is caused to revolve, and the rope *k* is wound upon the roller *j*. By these means motion is imparted to the brake-lever E, and the brakes are applied. As the rope *k* is drawn up tight, the strain of this rope assists in keeping the friction-roller *d* in contact with the axle, and a comparatively easy strain on the brake-rope is sufficient to apply the brakes. Furthermore, the strain exerted by the brake-rope on the lever D is increased by the leverage of the lever *f*, the distance of the roller *f'''* from the fulcrum of said lever being much larger than the distance of said fulcrum from the connecting-point of the rod *l*, as shown in Fig. 1. When the strain on the brake-rope is released, the brakes are taken off by the action of their springs, and the pendent lever falls back by its own inherent gravity and by that of the lever *f*; or it may be subjected to the action of a separate spring for the purpose of drawing it back as soon as the strain on the brake-rope ceases.

The friction-roller *d* is connected to its shaft

by means of two cone-disks, *n*, which work in conical seats in the opposite sides of the friction-roller, one of said disks being mounted firmly on the axle, while the other is pressed toward it by means of a spring, *o*, Fig. 2, the tension of which is regulated by a nut, *p*. By this arrangement the friction-roller can be set so that it will slip on its bearing before any of the ropes will break.

The car-wheel next to the friction-roller is cast with a long hub, *q*, (see Fig. 3,) and the friction-roller is intended to be so situated that it will bear on said hub, and thereby the necessity of securing a pulley on the axle is avoided.

What I claim as new, and desire to secure by Letters Patent, is—

1. The pendent lever *D*, carrying a shaft, *b*, with a friction-roller, *d*, and another shaft, *c*, with winding-rollers *i j*, both shafts *b* and *c* being situated below the fulcrum of said pendent lever, in combination with the brakes of a railroad-car, all constructed and operating substantially in the manner herein shown and described.

2. The multiplying-lever *f*, carrying rollers *f' f''*, in combination with the brake-rope *g* and pendent lever *D*, carrying friction-roller *d*, substantially as set forth.

JOSEPH STEGER.
